UNITED STATES PATENT OFFICE.

JOHN P. LACOUR, OF NEW YORK, N. Y.

ICE ANCHOR.

Application filed May 27, 1921. Serial No. 473,097.

To all whom it may concern:

Be it known that I, JOHN P. LACOUR, a citizen of the United States, residing at Westchester, New York city, in the county 5 of Bronx and State of New York, have invented new and useful Improvements in Ice Anchors, of which the following is a specification.

This invention relates to ice anchors for 10 use in certain methods of artificial production of ice, and one of the principal objects is to provide a device of this nature which may be used with other equipment now in use without necessitating changes in 15 said other equipment.

Another object is to produce a device of 20 this nature which is simple in construction cheap to manufacture, and highly efficient for the purpose for which it is designed.

Another object is to provide a device of 25 this nature which may be easily removed from the block of ice.

With these and other objects in view, the 30 invention resides in certain novel construction and combination and arrangement of parts, the essential features of which are hereinafter fully described, are specifically pointed out in the appended claims, and are illustrated in the accompanying drawing, in which:—

Figure 1 is a front view of my improved 35 ice anchor in place, the can being shown in section.

Figure 2 is a side elevation of the same.

Figure 3 is a top plan view.

Figure 4 is a section on the pivot line.

Like characters of reference refer to like parts in all views.

In the manufacture of artificial ice, cans 40 are partly filled with water, and then a brine is circulated about the cans to effect freezing of the contents. Some sort of anchor must be frozen into each cake of ice to insure easy removal of the same from 45 the can; and it is essential that these anchors have means for attaching a hook in the removal of the ice, and that they shall not rise high enough above the can to interfere with the cover which is closed down 50 over a tank containing a plurality of these cans.

Referring to the drawing in detail 10 55 represents a pair of identically formed L-shaped levers having depending arms 11 provided at the lower end with inwardly ex-

tending dogs 12 and having supporting lugs 13 drawn out laterally at the upper ends. Each lever 10 has also a horizontal arm 14 which when in place, extends toward the center of the can designated by numeral 15. 60 This horizontal arm 14 is twisted so that at the center of the can its broad face is vertical thus giving the narrow width necessary for using the lifting hooks at present installed in plants.

The two members 10 which form one ice anchor, have their horizontal arms 14 pivoted to each other at 16, and each arm 14 is projected beyond and below the pivot into a finger 17, the two fingers 17 defining a 70 recess 18 for the reception of the hook of the lifting mechanism. A brace 19 across the inner corner angle of each member 10 strengthens it, and while it is contemplated to construct this brace as an integral part 75 of the forging or casting, it may be constructed as a separate piece and riveted or otherwise secured to the main member.

In operation, the cans are partly filled 80 with water and the ice anchor is put in place with its lugs 13 resting on the upper edge of the can and with arms 11 resting flat against the inside of the can. It is to be understood that the water lever in the can is never high enough to cover any portion of braces 19. It will be noted that the top of the device extends only slightly above the top of the can so as not to interfere with the cover of the vat or tank in which the cans are placed. The water is 85 then frozen in the usual well known manner, and the ice is then thawed loose from the sides of the can, also in the usual well known manner. The hook of the lifting mechanism is then inserted in recess 18 and the block of ice is withdrawn from the can. During this lifting operation the legs 11 will obviously be pressed very tightly against the sides of the cake and the spurs or dogs 12 will be held firmly in the ice. When the 100 block is let down, it is only necessary to give the arms 14 a light blow near the pivot to loosen arms 11 and dogs 12 so that the anchor may be removed.

By this means I produce an ice anchor 105 which may be readily and quickly manipulated, which is positive in action and which does not require the thawing of any additional amount of the ice to effect release of the anchor, thus saving the ice and avoid- 110

ing the use of additional steam and steam
needle equipment.

What is claimed is:—

1. As an article of manufacture, an ice
5 anchor comprising vertical arms provided
with spurs at their lower ends, supporting
lugs at the upper ends of said arms, and
pivotally connected horizontal arms.

2. As an article of manufacture, an ice
10 anchor comprising vertical arms provided
with spurs at their lower ends, supporting
lugs at the upper ends of said arms, and
pivotally connected horizontal arms each ex-

tended beyond and downwardly from its
pivot.

3. As an article of manufacture, an ice
15 anchor comprising vertical arms provided
with spurs at their lower ends, supporting
lugs at the upper ends of said arms, and
pivotally connected horizontal arms each be-
ing twisted a quarter turn and each exten-
20 ded beyond and downwardly from its pivot.

In testimony whereof I have affixed my
signature.

JOHN P. LACOUR.
